United States Patent Office

Des. 191,800
Patented Nov. 21, 1961

191,800

SCALE STAND OR SIMILAR ARTICLE

John W. Westbrook, Box 343, Castle Rock, Colo.

Filed May 19, 1961, Ser. No. 65,248

Term of patent 14 years

(Cl. D52—10)

Fig. 2

Fig. 3

FIG. 1 is a perspective view of a scale stand or similar article showing my new design, the scale indicated in broken lines being for illustrative purposes only.

FIG. 2 is a top plan view thereof;

FIG. 3 is a front elevational view thereof; and

FIG. 4 is a side elevational view.

I claim:

The ornamental design for a scale stand or similar article, as shown and described.
